CLAIM

(57) The ornamental design for a solar light, as shown and described.

DESCRIPTION

FIG. 1 is a first perspective view of a solar light showing the claimed new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged view of the region designated FIG. 8 as shown in FIG. 7.

The broken lines shown on the drawings depict portions of the solar light that form no part of the claimed design.
